(57) **CLAIM**

We claim a new ornamental design for a spin mount with movable eyelet for gymnastics apparatus and equipment, as shown and described.

DESCRIPTION

FIG. 1 is a front perspective view of the spin mount with movable eyelet for gymnastics apparatus and equipment with the eyelet in a first position;

FIG. 2 is a front perspective view of the spin mount with movable eyelet for gymnastics apparatus and equipment with the eyelet in a second position;

FIG. 3 is a right-side view of FIG. 1, with the left side being identical;

FIG. 4 is a right-side view of FIG. 2, with the left side view being a mirror image;

FIG. 5 is a front elevation view of FIG. 2; and,

FIG. 6 is a top plan view of FIG. 1.
